UNITED STATES PATENT OFFICE

JOHN T. MOONEY, OF LA GRANGE, ILLINOIS

DESIGN FOR A TIMEPIECE DIAL

Application filed May 1, 1930. Serial No. 35,456. Term of patent 14 years.

To all whom it may concern:

Be it known that I, JOHN T. MOONEY, a citizen of the United States, residing at La Grange, county of Cook, State of Illinois, have invented a new, original, and ornamental Design for Timepiece Dials, of which the following is a specification, reference being had to the accompanying drawing, forming a part thereof.

The figure is a face view of a time piece dial, showing my new design.

I claim:

The ornamental design for a time piece dial, substantially as shown.

JOHN T. MOONEY.
